UNITED STATES PATENT OFFICE.

IRVIN S. CREAMER, OF PLEASANT HALL, PENNSYLVANIA.

LEVEL.

1,141,617.

Specification of Letters Patent.

Patented June 1, 1915.

Application filed April 22, 1913. Serial No. 762,950.

To all whom it may concern:

Be it known that I, IRVIN S. CREAMER, citizen of the United States, residing at Pleasant Hall, in the county of Franklin and State of Pennsylvania, have invented certain new and useful Improvements in Levels, of which the following is a specification.

My invention relates to leveling instruments and particularly to levels used by carpenters, masons and like craftsmen.

One object of my invention is the provision of a level, the body of which is formed in two longitudinally disposed sections hinged together at one end to permit them to be disposed at an angle to each other, and in this connection to provide a novel form of mounting for a screw whereby the free ends of the two sections may be relatively 20 shifted.

A further object is to provide a graduated scale attached to the end of one of the sections and an index member attached to the other section and movable over the scale 25 with the movement of the section to which it is attached whereby the inclination of one of said members or sections relative to the other member may be read in degrees or fractions of inches.

Another object is to provide a simple and novel means for adjusting the bubble glass.

A further object is to provide in connection with a level of the character described a bubble clinometer whereby the inclination 35 of the body may be read.

My invention is illustrated in the accompanying drawings wherein:

Figure 1 is a side elevation partly broken away of a level constructed in accordance 40 with my invention, the two sections of the legs or level being open. Fig. 2 is a rear end elevation of the level showing the means whereby the angle taken by one of the legs or sections to the other leg or section may be noted and read. Fig. 3 is an enlarged cross section on the line 3-3 of Fig. 1. Fig. 4 is an enlarged cross section on the line 4-4 of Fig. 1. Fig. 5 is an enlarged cross section on the line 5-5 of Fig. 1.

Corresponding and like parts are referred to in the following description and indicated in all the views of the accompanying drawings by the same reference characters.

Referring to these drawings, it will be

seen that the body of the level is composed of two legs or sections of wood or other suitable material, these sections being designated respectively 2 and 3. These sections have the same length and are hinged together at one end by means of the leaf members 4.

For the purpose of shifting the two sections of the body relative to each other, I provide a screw 5 which is formed with right and left hand screw threads, the middle of the screw being provided with a knurled disk 6 whereby the screw may be readily rotated, this disk being larger in diameter than the thickness of the sections 70 2 and 3. Each of the sections 2 and 3 is formed with a recess or chamber 7, and disposed in each recess or chamber is a plate 8, this plate having inwardly extending ears 9 which are perforated.

Pivottally mounted in the perforations of the ears are the nuts 10 which engage the right and left hand screw threads of the screw 5. The nuts 10 are mounted upon trunnions 11 which pass through the ears 9. 80 It will thus be seen that the nuts 10 may be rotated so as to permit the inclination of the screw 5 to alter as the sections 2 and 3 are moved from each other or toward each other.

The upper face of the section 2 is formed with a longitudinally extending recess 12 adapted to receive a bubble tube 13. This bubble tube at its end is supported within a cap 14, and passing through this cap and into the wood beneath the recess 12 is a screw 15, this screw being notched at its upper end at 16 to receive the metal of the cap 12. The metal around the opening through which this screw passes may be 95 pressed into this notch 16 after the screw is put in place or the cap may be formed in two sections, the edges of the sections intersecting the opening for the screw, and the two sections may be brought together to 100 force the metal around the opening into the notch 16 and then the sections may be soldered. The other end of the tube is supported in a cap 17, having an extension or tongue which is supported by means of a pin 18 driven into the wood at one end of the recess. This extension of the cap 17 provides means for pivotally supporting the adjacent end of the bubble tube so as to 105 permit the other end of the bubble tube to be 110

raised or lowered by means of the screw 15. By turning this screw in one direction or the other, the bubble tube may be delicately adjusted so as to make its operation accurate. 5 The wood on each side of the bubble tube is of course cut away as at 19 as is usual in levels, and the face of the bubble tube is protected by means of a plate 20 attached by screws or other suitable means to the face 10 of the member 2.

Disposed at the end of the section 3 opposite the hinge 4 is a graduated plate 21. The extremity of this plate is angularly bent as at 22 and attached to the face of the section 15 3 flush with the face of the section. Immediately beneath the plate 21 the end of the section 3 is cut away as at 23.

Attached to the end face of the member 2 at the free end thereof is an index carrying strip 24. The strip 21 is longitudinally slotted as at 26 as shown in Fig. 2 and the face of the strip on one side of the slot is graduated in fractions of an inch while on the other side of the slot the plate is graduated in degrees. The outer end of the strip 25 24 is outwardly bent and is notched as at 27. Inasmuch as the body of the strip 24 is wider than the slot 26, it will be obvious that the notched head 28 so formed will 30 positively engage with the walls of the slot 26 and will project slightly beyond those walls. This permits the scale to be accurately read with relation to the index pointer or bar 28 formed by the head and insures that the plate 21 shall be held in 35 proper relation to the index member 28 at all times. When the members 2 and 3 are closed against each other, the strip 24 will, of course, be received within the recess 23. 40 A further object in providing this interlock between the strip 24 and the plate 21, is to reduce the likelihood of one of the sections 2 being laterally shifted relative to the other section and to take off torsional strain from the hinge 4. This arrangement provides for a sliding engagement between the extremity of the section 2 and the extremity of the section 3. 45

The upper section 2 is cut away in the arc 50 of a circle for the reception of a circular casing designated 29 and illustrated in Fig. 3. This casing is formed with the annular marginal flange 30 which is disposed upon the face of the member 2 and extends down 55 below the inner edge of said member as illustrated in Fig. 1. This face is provided with degree graduations.

Passing centrally through the casing 29 60 is a pivot screw 31 upon which is pivotally supported a nearly circular bubble glass holder 32. The upper portion of the bubble glass holder is transversely cut away and formed with the upwardly projecting ears 33, and disposed between said ears and carried thereby is a bubble glass 34 of the usual

character. The face of the member 32 is provided with the diametrically disposed notches or other indicating marks designated 35 which coact with the graduations on the annular dial flange 30. It will be 70 seen that the preponderance of the weight is below the pivotal center of the member, that as a consequence it will of itself swing into a horizontal position. In order that it may be adjusted to a true horizontal position, however, if desired, I provide the bubble tube 34 supported between the ears or lugs 33. By this means after the body of the level has been placed against an inclined object, the member 32 may be rotated gradually by hand to a true horizontal position and then the angle of the level with relation to a horizontal plane may be 75 readily determined by reading the degree number on the dial in conjunction with one 80 of the pointers or index notchers 34.

In order to permit the level to be readily carried and handled, I cut away the side faces of the sections 2 and 3 adjacent the inner faces thereof as at 36. 90

The use of my invention is obvious. The inclination of a surface relative to the horizontal may be easily determined by placing the level upon the surface and then turning upon the screw 6 until the upper section rises 95 to a horizontal position which is indicated by the bubble glass 13. The inclination of the surface measured may then be read by means of the scale 21 and the pointer or index 100 28. The scale may be either read in inches or degrees as desired and will indicate either in inches or degrees the fall of an object, or the inclination of a surface. Where the level as a whole is intended to be used for determining a degree of inclination, the pivoted bubble carrier 32 is used in conjunction with the scale 30 in the manner previously set forth. The inclination or batter of a wall may also 105 be determined by this instrument in an obvious manner. 110

What I claim is:

1. A level of the character described composed of two longitudinal sections hingedly connected at one end, the inner face of the sections being recessed, plates disposed upon the inner faces of the sections and having inwardly turned ears extending into said recesses, nuts disposed between said ears and having trunnions pivotally engaging the ears, a right and left hand screw engaging 115 said nuts, the screw being provided with a disk at its middle whereby it may be rotated.

2. A level of the character described including two longitudinal sections hingedly 120 connected at one end, means disposed between the ends of the sections for shifting them into parallel or divergent relation, a slotted scale plate attached to the end face of one of the sections and having gradu- 125 130

tions on its face, the end of the said section beneath the slotted plate being partially cut away to form a recess, and an angular strip attached to the other section having its 5 extremity outwardly bent and extended through the slot, the terminal portion of the bent extremity being laterally widened to extend laterally over the face of the recess.

10 3. A level of the character described formed in two longitudinal sections hingedly connected at one end, the inner face of each of the sections being recessed, a plate disposed against the inner face of each section 15 and extending over said recess, said plate having angularly bent ears extending into the recess, nuts pivotally mounted one in each pair of ears, and a right and left hand screw extending through said nuts, the mid- 20 dle of the screw being formed with a head greater in diameter than the width of the

sections whereby the screw may be manipulated.

4. A level of the character described having a bubble glass recess upon its face, a 25 bubble glass therein, a cap on one end of the bubble glass and having a projecting tongue, a pin engaging the tongue and permitting the bubble glass to have pivotal movement with relation to the pin, a cap 30 mounted on the other end of the glass and having a perforation, and a screw passing through said perforation and into the body of the level, said screw being notched to engage the cap. 35

In testimony whereof I affix my signature in presence of two witnesses.
